(57) **CLAIM**

The ornamental design for an article of furniture, as shown and described.

DESCRIPTION

FIG. 1 is a perspective view of an article of furniture showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken away portions shown in the drawing figures are meant to indicate indeterminate length and that no specific length other than what is shown is claimed. The broken lines depict portions of the article that form no part of the claimed design.

1 Claim, 5 Drawing Sheets
